ENGINE STARTER CONTROL SWITCH.

Kenneth P. Tota, Elmira, N. Y., assignor to Bendix Aviation Corporation, a corporation of Delaware

Application September 20, 1946, Serial No. 698,162

6 Claims. (Cl. 200—59)

1

The present invention relates to engine starter control switch and more particularly to a mechanical locking device for preventing closure of a starting switch when the engine is under motion.

In those types of engine starter gearing in which the gearing is normally disconnected and is engaged in order to perform the starting operation, it is undesirable that such engagement should take place when the engine is rotating forward, since such engagement is noisy and tends to mill off the ends of the gear teeth. Engagement while the engine is rotating backward for any reason has the further hazard that it imposes shock loads on the gearing which may be destructive.

Various running functions of the engine have heretofore been utilized either singly or in combination for supplemental action to prevent such inopportune actuation of the starting mechanism. Such indirect approaches to the problem have been considerably handicapped, however, by the time lag necessary for the rotation of the engine to produce the functions to an operative degree, and by the complication necessary to provide such protection during phases of operation of the engine.

It is an object of the present invention to provide a novel unitary starter control which is so connected to the engine as to be operated directly by motion of a moving part thereof to thereby positively prevent actuation of the starting mechanism when the engine is rotating.

It is another object to provide such a device comprising a latching mechanism for preventing closure of the starting switch, which mechanism is rendered operative by rotation of the engine in either direction.

It is another object to provide such a device which is unaffected by rotation of the engine after the starting mechanism is energized, so as not to interrupt the cranking operation.

Further objects and advantages will be apparent from the following description taken in connection with the accompanying drawing, in which:

Fig. 1 is a semi-diagrammatic illustration of a preferred embodiment of the invention, the starting switch and controlling mechanism being shown in elevation, partly broken away and in section;

2

Fig. 2 is a section taken substantially on the line 2—2 of Fig. 1, showing the parts in the positions assumed when the control member of the starting switch engages the engine member during closing of the switch;

Fig. 3 is a view similar to Fig. 2 showing the parts in cranking position; and

Fig. 4 is a similar view showing the parts in the positions assumed when the starting switch is actuated while the engine is rotating.

In Fig. 1 of the drawing, there is illustrated a starting system including a battery 1 grounded at 2 and connected by a lead 3 to a contact 4 of a magnetic starting switch indicated generally by numeral 5. The starting switch 5 comprises a magnetic plunger 6 having a bridging contact 7 adapted to connect contact 4 to a second stationary contact 8. Contact 8 is connected by a lead 9 to the starting motor SM which is grounded at 11 to complete the starting circuit.

Switch plunger 6 is normally maintained in its upper position as illustrated in Fig. 1 by means of a spring 12, and a solenoid 13 is provided for pulling the plunger down so as to close the starting switch. Solenoid 13 is mounted in a cylindrical frame 14 providing a bearing 15 for the switch plunger. One end of the solenoid 13 is connected through a manually operable switch 16 to the battery lead 3 and the opposite end is grounded as indicated at 17 to complete the control circuit.

A control member 18 is pivotally connected to the lower end of the switch plunger 6 as by means of a pin 19 traversing the upper end of the control member and a bracket member 21 fixed as indicated at 22 to the lower end of the switch plunger. The pin 19 is arranged to slide in slots 23, 24 in the lower end of the housing 14, and is prevented from longitudinal movement by suitable means such as a head 25 on one end of the pin, and a thrust washer 26 attached to the other end. Longitudinal movement of the bracket 21 and control member 18 on the pin 19 is prevented by thrust rings 27 and 28 seated in grooves on the pin. Control member 18 is normally maintained in alignment with the switch plunger 6 by means of a tension spring 29 pinned to the adjacent ends of the control member and plunger.

The lower end of the control member 18 is provided with a yielding telescopic portion in the

form of a block 31 of suitable material such as fiber slidably mounted in the lower end of the control member and retained therein by means of a rivet 32, traversing slots 33, 34 in the control member. A spring 35 is arranged to yieldably hold the block 31 in extended relation to the control member 18.

The starting switch assembly with the control member 18 projecting therefrom is mounted in any suitable manner adjacent any appropriate moving part 36 such as the flywheel of the engine to be started, in such a manner that the fiber block 31 will engage such part 36 when the switch plunger 6 is actuated by the solenoid 13, such engagement taking place substantially before closure of the starting switch as shown in Fig. 2. It will be understood that the part 36 may be any moving part of the engine itself, or any part which is connected so as to move when the engine is rotating such as the fan or generator pulley, fan belt, etc., the only requirement being that the device be so installed that the movement of the part 36 will cause the control member to swing laterally about the pivot pin 19 when the fiber block 31 engages the moving part.

In order to prevent closure of the starting switch 5 when the engine is rotating, abutment means are provided for engaging a portion of the control member 18 when it is deflected laterally from its normal rectilinear path by the engagement of the fiber block 31 with the moving engine part 36. As best shown in Figs. 2, 3 and 4, this abutment means is in the form of a pair of stop members 37, 38 fixed as indicated at 39 and 41 to the bottom of the solenoid casing 14 and provided with seats 42 and 43 arranged to receive a pin 44 extending laterally from the control member 18 so as to arrest the movement of the control member and consequently of the switch plunger 6. The stop members 37, 38 are separated by a sufficient space 45 to permit the passage of the pin 44 when the control member 18 is maintained in alignment with the switch plunger 6 by the spring 29. If, however, the control member is diverted from its normal path by the engagement of fiber block 31 with the engine part 36 when the latter is moving in either direction, the pin 44 will move laterally into one or the other of the seats 42, 43, depending on the direction of motion of the engine member, and thereby prevent closure of the starting switch.

The lower portions of the stop members 37, 38 are inclined as shown at 46 and 47 so as to guide the pin 44 into the space 45 when the switch plunger 6 returns to its normal position after closure of the starting switch.

In operation, starting with the parts in idle position as shown in Fig. 1, closure of control switch 16 by the operator energizes the solenoid 13 which attracts the switch plunger 6 causing the plunger to move downward, projecting the control member 18 and causing the fiber block 31 to engage the engine part 36, as illustrated in Fig. 2. If the engine part is stationary at this time, the pin 44 passes through the space 45 between the abutments 37, 38, such further movement of the control member 18 being permitted by the yielding telescopic movement of the fiber block 31 therein. When the bridging contact 7 engages the stationary contacts 4, 8, the starting motor SM is energized to crank the engine. The consequent rotation of the engine part 36 causes the control member 18 to be moved laterally into the position shown in Fig. 3, but such movement merely relieves the pressure of the

fiber block 31 on the engine part 36 without interrupting the cranking operation. When the engine starts, opening of the switch 16 by the operator allows the parts to return to their idle positions.

If, when the starting control switch 16 is closed, the engine part 36 is rotating in either direction, as soon as the fiber block 31 engages said engine part, the former will be immediately diverted from its rectilinear path so as to bring the pin 44 into position to engage one or the other of the seats 42, 43 of the abutments 37, 38. Further movement of the switch plunger 6 is thus prevented, and the starting switch is held open as shown in Fig. 4.

In some instances, it may be found desirable to provide means for delaying the longitudinal movement of the switch plunger 6 in order to insure ample time for actuation of the control member 18 by the engine member 36. As shown in Fig. 1, this may be accomplished by causing the bearing 15 and the core 48 of the solenoid 13 to cooperate with the switch plunger 6 to form a dash-pot. For this purpose, a cup valve member 49 may be attached as illustrated to the switch plunger 6 and a bleeder opening 51 formed through the bearing 15 to control the escape of air from the dash-pot.

Although but one embodiment of the invention has been shown and described in detail, it will be understood that other embodiments are possible and various changes may be made in the design and arrangement of the parts without departing from the spirit of the invention as set forth in the claims appended hereto.

What is claimed is:

1. In an engine starter control switch, a switch element bodily movable to close the switch, a control member movable by said element into engagement with a moving part and arranged to be diverted by said engagement out of its normal path of movement, and an abutment for arresting the control member when so diverted to thereby prevent the switch element from closing the switch.
2. In an engine starter control switch, a bodily movable element for closing the switch, a member so connected to said element as to be movable thereby into engagement with a moving part prior to closure of the switch, and to be deflected from its normal path of movement by such engagement when said part is in motion, and an abutment for arresting the movement of the member when so deflected to thereby prevent the movable element from closing the switch.
3. An engine starter control switch having an element movable to close and open the switch, a control member connected to be moved by the switch element into engagement with a movable part prior to closure of the starting switch and having freedom for lateral deflection by such engagement if the part is in motion, said control member being constructed to yield and permit closure of the switch after such engagement, and an abutment means engaged by the control member when deflected by movement of said movable part, to thereby prevent the switch element from moving to closed position.
4. An engine starter control switch as set forth in claim 3, including further yielding means normally holding the control member in undeflected relation to the switch element.
5. An engine starter control switch having a movable element, a control member pivotally connected to the switch element and movable

70 in claim 3, including further yielding means normally holding the control member in undeflected relation to the switch element.

75 An engine starter control switch having a movable element, a control member pivotally connected to the switch element and movable

thereby into engagement with a moving part prior to closure of the starting switch, and an abutment arresting the movement of the control member when the latter is deflected by engagement with the moving part.

6. In an engine starter control switch, manually controllable means for causing closure of the switch, and means for preventing undesired closure of the switch including a control member connected to said switch to be moved rectilinearly by closure thereof into engagement with a movable part, said control member being movable laterally by such engagement when said part is in motion, and an abutment means engaged by said control member when so moved laterally, to

arrest its forward motion, and thereby prevent closure of the switch.
